2,040,474

APPARATUS FOR PROCESSING METAL WORKPIECES

Robert U. Geib, Jr., Edgewood, Pa.

Application October 9, 1933, Serial No. 692,875

7 Claims. (Cl. 80—13)

This invention relates to the manufacture of seamless pipes and tubes from solid rounds, or "billets", and to any and all of the operations used therein, such as "piercing", "expanding", "elongating", "reducing", or any combination thereof.

In the manufacture of seamless pipes and tubes by the use of power-actuated metal-working rolls considerable difficulty has been experienced in obtaining flawless products. The processing 10 of the metal of the work-piece by the metal-working rolls must be carefully controlled, otherwise "upsetting" will occur, or grooves and ridges, annular bulging, tearing, uneven wall thickness, etc., will appear in the product. In addition, a 15 great many other limitations are encountered, such as the inability of the rolls to effect the desired amount of processing without resorting to numerous subsequent operations, difficulty in obtaining maximum speed of production, and the 20 tendency of most metal-working rolls to draw metal into the inlet of the pass at a greater rate of speed than that at which it is expelled from the outlet.

There have been some recent developments 25 which overcome a great many of the difficulties referred to, and also greatly increase the speed of production of all types of mills. According to these new principles, guiding members are positioned intermediate the usual metal-working 30 rolls and consist of power-actuated grooved rolls rotating on axes substantially at right angles to the pass defined by the metal-working rolls, and each having a peripheral velocity in the direction of and greater than the longitudinal travel 35 of a work-piece progressing therethrough.

The effect of these rotating guide rolls is to 40 divert longitudinally the peripheral flow of the metal of the work-piece which is occasioned by the metal-working rolls. For this reason the guide rolls should cause a tension or at least materially reduce the compression of the metal in 45 that portion of the pass wherein the greater part of the processing is done.

The guide rolls are positioned vertically relative to one another in such manner as to permit 50 the work-piece to assume an elliptical shape, or "ovality." If they are insufficiently spaced, the work-piece will "freeze" on the mandrel. The maximum distance at which the guide rolls may 55 be spaced from the mandrel is that at which the metal of the work-piece will permit repeated bending in its changes to and from cylindrical and elliptical formation. The pressure of the guide rolls should be as small as possible, but at the

same time the distortion of the work-piece should be limited as much as possible.

If the metal of the work-piece, either in whole or in part, is not in a desired state of plasticity, occasioned by insufficient heating, the peripheral speed, or rate of rotation, of the guide rolls should be decreased. On the other hand, if the metal is very highly heated, and therefore unusually plastic, advantage should be taken of this condition and the peripheral flow thereof diverted 10 longitudinally at a more rapid rate, or undue distortion will occur.

One object of the invention is the provision of a novel apparatus for processing metal work-pieces in such manner as to consistently obtain 15 flawless pipes and tubes of the "seamless" type, and by the use of which the metal of the work-piece is processed in direct ratio to its plasticity.

Another object is to provide a novel means for controlling the "ovality", or distortion, inherent 20 in seamless pipe and tube methods, in such manner as to completely avoid the possibility of flaws, or defects, in the processed work-piece.

A further object is to provide a novel apparatus 25 of the class described in which the metal of the work-piece is diverted from a tangential path of travel, imposed by helically acting metal-working rolls, into a longitudinal direction, the diversion being exerted to a degree determined by the plasticity of the metal.

A still further object is to provide a novel apparatus 30 for automatically controlling the speed of diversion in accordance with the temperature of various areas in single, or successive, work-pieces, separate means compensating for the 35 varying degrees of plasticity characteristic of different metals at the same temperature.

These and further objects of the invention will 40 be apparent after referring to the drawing, in which:

Figure 1 is a plan of the apparatus of the invention.

Figure 2 is a sectional elevation of the apparatus of Figure 1 as used in piercing operations.

Referring more particularly to the drawing, 45 the numeral 2 designates a pair of conventional cone-shaped metal-working rolls, commonly used in the manufacture of seamless pipes and tubes which, when taken together, provide convergent surfaces 2^a and divergent surfaces 2^b. The metal-working rolls 2 are suitably power actuated, as by means of the adjacent motors 3.

A pair of grooved guide rolls 4 are mounted on 50 rotatable shafts 5, one of which is disposed above and the other below the "pass-line" of the mill, 55

as defined by the metal-working rolls 2, and at substantial right angles thereto. In view of the fact that the metal of the work-piece is restrained from longitudinal movement while in contact with the most adjacent surfaces of the metal-working rolls 2 where the greatest reduction in wall thickness occurs, the surfaces of the guide rolls 4 are so disposed as to permit their surfaces to contact with the work-piece substantially in the outlet of the mill, as defined by the divergent surfaces 2^b of the metal-working rolls, for the reason that the metal of the work piece displaced by the guide rolls will be free at this point to move in a longitudinal direction.

15 A piercing plug 6 is mounted on a mandrel bar 6^a and positioned with its point substantially at the "gorge" or most constricted portion of the pass, as defined by the metal-working rolls 2, which is where the convergent surfaces 2^a ad-

20 join the divergent surfaces 2^b.

The shafts 5, on which the guide rolls 4 are mounted, are geared together in any suitable manner and are disposed in a common vertical plane. The upper shaft 5, or that which is positioned above the "pass-line" of the mill, is connected to a selective gear reduction transmission unit 7, which is associated with a motor 8, a lever 7^a being provided for enabling the changing of gears. It will be readily understood that the 25 other of the shafts 5 may be connected to the selective gear reduction transmission unit 7, in any suitable manner which, however, is not shown, it being purely nominal and a matter only of convenience.

35 A heat-responsive circuit making-and-breaking device, such as a conventional photoelectric control unit, generally indicated at 9, is "trained" on a work-piece A being processed by the mill at a point immediately before it is contacted by 40 the convergent surfaces 2^a of the work rolls, and provides means for registering a relatively wide temperature range inherent in the work-piece at this point. The heat-responsive circuit making and breaking device 9 is operatively associated with a motor control device 10 which is 45 connected to the motor 8 for transposing the various temperature ranges inherent in the work-piece to accordingly vary the peripheral speed of the guide rolls 4, the function of selective gear reduction transmission unit 7 being to further and adjustably modify this speed control.

In operation, a work-piece A, in the present instance a solid round or "billet", which is to be pierced, is introduced into the converging surfaces 55 2^a of the work rolls, where it is "necked down" to open its central fibers prior to its introduction to the piercing plug 6. This "necking down" operation directs the billet into a vertical deformation, or "ovality", indicated at A' 60 in Figure 2, in addition to which a tendency toward elongation will be present.

From the "gorge", or most constricted portion, where the actual piercing occurs, this tendency toward ovality is much greater as the work-piece progresses through the outlet of the mill and should be limited as much as possible in order to avoid defects in the processed work-piece. If the work-piece is very highly heated, and therefore unusually plastic, this "ovality" 70 will be excessive, as indicated in broken lines at A² in Figure 2, both before and after the metal is in the "gorge" if the peripheral speed of the guide rolls 4 is insufficient to tension the metal, or at least to materially reduce the compression thereof, while it is adjacent the "gorge".

In accordance with the teaching of the present invention, the peripheral speed of the guide rolls 4 will be automatically increased immediately by a high heat area inherent in the work-piece. A progresses into the range of the heat-responsive control unit 9, which is disposed slightly in advance of the metal-working rolls 2, thereby actuating the motor control device 10 and accordingly the motor 8. The gear changing lever 7^a having previously been adjusted to modify the 10 rotational effect of the motor 8 in order to compensate for the characteristics of the metal being processed as related to its temperature, the peripheral speed of the guide rolls 4 will be increased in exact ratio to the plasticity of the 15 metal and act to tension the same and divert its peripheral path of travel, imposed by the metal-working rolls 2, in a longitudinal direction, as shown in full line at A³ in Figure 2. If desired, the heat responsive circuit making and 20 breaking device, or photoelectric control unit 9, may be disconnected, and the motor control device 10 actuated manually by an operator who is in a position to closely observe the condition 25 of the work-piece.

The relativity of the excessive vertical "ovality" or, "bulging", indicated in broken lines at A² to the "gorge" of the metal-working rolls 2 is illustrated by the line 2^x, while the line 4^x indicates the beginning of the area of guide roll contact. 30 In this area the metal of the work-piece will closely follow the contour of the guide rolls as indicated at A⁴ until the end of the zone where the work-piece is internally supported by the piercing plug 6 is reached. This point is indicated by 35 the line 6^x, and it is here, or closely adjacent, that the area of guide roll contact terminates.

After the termination of guide roll contact, the metal of the work-piece will be no longer restrained in a vertical direction, and due to the 40 contour of the divergent surfaces 2^b of the work rolls it will gradually taper from the vertical "ovality", as shown at A⁵. While in this area of work roll contact the work-piece will be 45 "rounded-up".

The last point of work roll contact is illustrated by the line 2^z, and from here the work-piece progresses from the mill in the form of a perfect round, as indicated at A⁶.

In an application filed October 9, 1933, entitled Apparatus for processing tubular work-pieces, and bearing Serial No. 692,876, I have described a method of varying the longitudinal flow by shifting the guide rolls along the work-piece to points determined by the plasticity of 55 the metal; effecting such shift either automatically under control of the temperature, or manually in accordance with the worker's observation of the plasticity or his knowledge of the composition of the metal and consequently 60 its plasticity, or in both of these ways.

In an application, filed October 9, 1933, entitled Apparatus for processing metal work-pieces, and bearing Serial No. 692,877, I have described a method and apparatus for achieving 65 the same result by automatically varying the pressure of the guide rolls on the work-piece, this also being accomplished by manual control, as far as is necessary.

The present invention is directed broadly to 70 the inclusion of any, or all, of the devices and methods described in said copending applications and in the present case, and to any other methods and devices for achieving the desired result in equivalent ways.

It is to be understood that my invention is intended to cover any satisfactory secondary modifier for the final effect of motor 8 on the peripheral speed of guide rolls 4 in lieu of the selective gear reduction transmission unit 7; that any suitable heat-responsive circuit maker and breaker may be substituted for the suggested photoelectric control unit 9; and that while I have shown and described one specific embodiment of other details I do not wish to be limited exactly thereto, since various modifications may be made without departing from the scope of my invention, as defined in the following claims.

I claim:

- 15 1. Apparatus for processing tubular work-pieces comprising, in combination, a pair of power-actuated metal-working rolls, means for continuously diverting the tangential flow of the metal of the work-piece into a longitudinal direction, means for regulating the speed of said diversion at a rate varying in accordance with the temperature of the work-piece, and secondary regulating means for further modifying said speed of diversion in accordance with the resistance to displacement of the metal of the work-piece.
- 20 2. Apparatus for processing tubular work-pieces comprising, in combination, a pair of power-actuated metal-working rolls, at least one guide roll having its axis substantially at right angles with respect to the pass line defined by said work and guide rolls, means for rotating said guide roll with its periphery in contact with the work-piece, means for regulating the speed of said rotation in accordance with the temperature of said work-piece, and secondary regulating means for further modifying the speed of rotation in accordance with the resistance to displacement of the metal of the work-piece.
- 25 3. Apparatus for processing tubular metal work-pieces comprising means for helically working the metal of said work-piece, in combination with means for diverting said helically worked metal in a longitudinal direction, means for determining the temperature of said work-piece and automatically regulating the diverting means in accordance therewith, and means for modifying the effect of said last named means in accordance with the resistance of the metal of the work-piece to displacement.
- 40 4. Apparatus for processing tubular metal work-pieces comprising, in combination, a plurality of power-actuated metal-working rolls, at least one guide roll having its axis substantially at

right angles with respect to the pass line defined by said metal-working and guide rolls, means for rotating said guide roll with its periphery in contact with the work-piece, a heat-responsive control device for regulating the rotative speed of said guide roll in accordance with the temperature of said work-piece, and adjustable means for further modifying the rotative speed of said guide roll in accordance with the resistance to displacement of the metal of the work-piece.

5 5. Apparatus for processing tubular work-pieces comprising, in combination, a pair of power-actuated metal-working rolls, means for continuously diverting the tangential flow of the metal of the work-piece into a longitudinal direction, means for regulating the speed of said diversion in such manner as to minimize the distortion of the work-piece, and secondary means for modifying the effect of said regulating means.

10 6. Apparatus for manufacturing pipes and tubes comprising a plurality of power-actuated metal-working rolls, said metal-working rolls being constructed and arranged to move the work-piece longitudinally and work the material of which it is composed; whereby portions of the work-piece are caused to bulge intermediate the metal-working rolls, at least one power-actuated guide roll disposed intermediate said metal-working rolls for limiting the bulging of the material of the work-piece and moving it longitudinally of its axis, in combination with means for registering the temperature of the work-piece, and means operated by said temperature-registering means for governing the speed of rotation of said power-actuated guide roll.

15 7. Apparatus for manufacturing pipes and tubes comprising a plurality of power-actuated metal-working rolls, said metal-working rolls being constructed and arranged to move the work-piece longitudinally and work the material of which it is composed, whereby portions of the work-piece are caused to bulge intermediate the metal-working rolls, at least one power-actuated guide roll disposed intermediate said metal-working rolls for limiting the bulging of the material of the work-piece and moving it longitudinally of its axis, in combination with means for registering the temperature of the work-piece, means operated by said temperature-registering means for governing the speed of rotation of said power-actuated guide roll, and separate means for modifying the operation of said last named means.
